UNITED STATES PATENT OFFICE.

WILLIAM JOSEPH BRADLEY, OF TROY, NEW YORK.

BOILER-FIUE CLEANER.

No. 926,722.

Specification of Letters Patent. Patented July 6, 1909.

Application filed December 7, 1903. Serial No. 435,350.

To all whom it may concern:

Be it known that I, WILLIAM J. BRADLEY, a citizen of the United States, residing at Troy, in the county of Rensselaer and State 5 of New York, have invented a new and useful Improvement in Boiler-Tube Cleaners, of which the following is a specification.

This invention relates to certain new and useful improvements in steam-boiler tube or 10 flue cleaners of that type which directs jets of steam into and through the tubes or flues from the rear end of the boiler removing therefrom the soot and other extraneous matter and projecting the same out through 15 the chimney or stack.

My present invention is also an improvement on the devices disclosed in United States Letters Patent #868,403 issued to me on October 15, 1907 and my application 20 Serial No. 423,898, filed March 28, 1908. In the construction shown in Letters Patent #868,403, the operator could not positively determine what boiler tubes had been cleaned and in addition, the steam from the 25 inner end of the discharge outlet frequently reached the boiler arch causing disintegration thereof. Both of these difficulties I have overcome in my present invention.

In my application for United States Letters Patent, Serial No. 423,898, filed March 28, 1908 I disclosed a type of cleaner which 30 was perfectly operative and which obviated the difficulties set forth above in connection with the device covered by United States 35 Letters Patent #868,403 but I have discovered a better construction with fewer parts for rotating the discharge end of the steam outlet and also imparting thereto in addition a radial motion by means of which 40 each and every boiler tube is blown clear and clean of all soot or other extraneous matter.

I am aware of other patents than mine 45 which have been allowed on boiler tube cleaners but experience has demonstrated their lack of ability to perform the work for which they were intended especially in cases where the boiler tube area was extensive or the flues were of great length.

In my new construction I secure the entrance of the steam into the boiler flues in a 50 more direct line and have reduced to a minimum the chance of difficulty arising from rust, corrosion or heat in connection with securing the radial motion of the steam outlet.

55 My new shifting mechanism consists of a

fork and block operated by a shaft turned by a handle or controller which carries a spring pin engaging at set points with counter borings on the face or rim of the hand wheel. These set points are marked to indicate to 60 the operator the particular rows of boiler tubes into which the steam is being directed from the steam outlet. I have also deflected the upper section of the funnel inclosing the steam outlet to prevent the steam from 65 reaching the boiler arch, and have secured greater ease of operation by lengthening the cylindrical sleeve and steam outlet thereby increasing the leverage of the shifting mechanism. 70

In the accompanying drawings Figure 1 is a side elevation of my device. Fig. 2 is a side elevation of the cylindrical sleeve shown detached from the blower. Fig. 3 is a view of the front end of same. Fig. 4 is a view of 75 the rear end of same. Fig. 5 is a longitudinal cross section. Fig. 6 is a sectional view of the shifting fork and block on the line x^1-x^1 in Fig. 5. Fig. 7 is a sectional view on line x^2-x^2 in Fig. 5. Fig. 8 is a side view of 80 my device showing the supply pipe cut away inside of rear sleeve and the shield in section to display the internal mechanism in perspective. Fig. 9 is an enlarged view of the hand wheel and controller. Fig. 10 is an enlarged view of the inner end of the cylindrical sleeve showing in dotted lines the 85 movement of slot. Fig. 11 is a sectional view on line x^4-x^4 of Fig. 15. Fig. 12 is a sectional view on line x^5-x^5 of Fig. 15. Fig. 90 13 is a perspective view of recessed end of valve stem. Fig. 14 is a side view of shifting fork and block. Fig. 15 is a horizontal sectional view of cylindrical sleeve. Fig. 16 is a vertical, sectional view of cylindrical 95 sleeve. Fig. 17 is a side elevation of valve stem. Fig. 18 is a plan view of the shifting fork and block. Fig. 19 is a front view of the shifting fork and block. Fig. 20 is a side view of my invention showing the same set 100 into the rear wall of a furnace which is shown in vertical longitudinal section.

In the drawings, 21 is a rigid steam supply pipe around which the blower revolves, 22 is the extension of same into the inner part of 105 the device, 23, 23, are the frame supporting rods and 24 and 25 indicate the rear collar supporting the device.

26 is a spoked hand wheel for rotating the device and 33 is the controller, carrying a 110

pin 35 which engages with counterbored holes in the wheel 26. This pin is held in engagement by the spring 36 and 37 is the releasing handle thereof.

5 38 is a bolt attaching the releasing handle 37 to the controller 33, and 39 is the cupped handle of the latter.

The counterbored holes in the surface of the wheel 26, (as shown in Fig. 8) serve to indicate what rows of tubes are being cleaned, the movement of the controller 33 to the various counterbored holes imparting to the steam outlet 29, the radial motion in the slot 50.

15 27 is a plug threaded on the outer end to engage with the supply pipe 22, and on its inner end to engage with the rear end of the sleeve 60 in an absolutely steam tight bearing. The inner end of this plug is of sufficient length to extend into the cupped end of the valve stem 28, which moves forward to its seat and is sealed tight when steam enters through the supply pipe.

28 indicates the hollow valve stem, the 25 bent or offset end of which, 29 contains two apertures through which the steam issues. The outer end of this valve stem is slightly rounded and is ground steam tight to engage with the circular seat 49, in the rear of the 30 cylindrical sleeve 60, and it is also cupped to receive the inner end of the rear plug 27, thus forming an absolutely steam tight compartment. When the blower is not in use the valve stem will fall back off the steam 35 tight bearing, thereby preventing rust, corrosion or the accumulation of pressure from the leakage of steam through the supply connections.

32 indicates a shaft rigidly attached at the 40 outer end of the cleaner to one end of the controller 33, passing through the rear sleeve 26 into the opening 63° and entering in the block 45, the other section of which is 45 shaped to receive the hollow valve stem 28.

45 This fork and block describe a swing and circular movement each of which is distinct in the travel of the steam outlet required to decrease the projection angle of the steam jets. The two parts of the fork and block in 50 performing their function move as follows: The block portion moves in a plane parallel to the axis of the valve stem seat, the fork portion moving in a plane at right angles to the axis of the valve stem seat, the two portions being connected by a pivotal stud 61, threaded into the block portion and allowing the fork portion to move independently of the block portion.

41 is a soft packing held by the shield 42, 60 and 34 is a binding nut for the stuffing box. The shield 42 is intended to protect the mechanism inside from any injury or interference by reason of defects in the brick work of the boiler wall.

65 The rear portion of the funnel is indicated

27 43, and 46 is the deflecting upper section of the same which serves to prevent the jets of steam from reaching the brick work of the boiler arch. 47 is the lower section of the funnel.

48 is the inner end of the rear plug 27, and 49 is a ring making said plug steam tight.

47 is the slightly rounded seat of the valve stem 28, and 49 is a circular seat in the rear of the cylindrical sleeve 60. The split collar 54-55 is held together by the tap bolts 52-53.

The inner threaded end of the hand wheel 56, is indicated by 54, and 55 is the outer threaded end of same.

50 is a cylindrical sleeve one end of which, 55 is threaded to receive the threaded hollow plug 27 and the other end of which 59 has a slot through which projects the end 29, of the valve stem 28. In this cylindrical sleeve is a 55 bored hole 62, through which the shifting mechanism is placed in position and 63 is a stop to hold it in position after adjustment.

61 indicates a cupped recess in the rear end of the valve stem 28, and 64 is a steam tight 90 compartment between the valve stem 28, and the rear plug 27. (See Fig. 15.)

In Fig. 20, the boiler is indicated by 66, the boiler tubes by 67, the rear boiler wall by 68, the inlet valves by 69 and 70, the supply pipe 95 by 71, the drip valve by 72 and an air space in the rear boiler wall by 73.

I have found it possible with this construction, to blow cleanly, boilers with the widest tube area, and the reduction in the angle of the projection of the jets of steam insures the entrance of the steam into the boiler tubes in a much more direct line thereby removing all extraneous matter from the entire length of the tubes. The steam supply always enters the valve stem in a direct line regardless of the angle at which the steam outlet is set.

In operating my device the steam is admitted by the valves 69 and 70 to the supply 110 pipe 71 and 72 from whence it passes through the rear plug 27 directly into the valve stem 28 and out of the apertures 30 and 31 into the boiler tubes 67, 68. The impact of the steam when admitted forces the seat 47 of the valve 115 stem against the seat 49 of the cylindrical sleeve making an absolutely steam tight connection and concentrating thereby the entire pressure of the boiler through the apertures 30 and 31, so that the steam will carry 120 the entire length of the longest boiler tubes. The operator then sets the controller 33 in one of the counterbored holes in the rim of the wheel 26, each of which is marked to indicate what rows of tubes will be reached by 125 the steam jets issuing from the apertures 30 and 31 and then rotates the blower once or more around by means of the hand wheel 26. The controller is then shifted successively to the other counterbored holes, the blower is 130

revolved at each shift and when this is completed the entire flue space will be thoroughly cleaned.

Having thus described my invention, I claim as new and desire to secure by Letters Patent:

1. An apparatus of the class described, comprising an inlet pipe; a rear plug connecting with same; a sleeve connecting with said rear plug provided with a slot in its inner end and having a valve seat; a hollow valve stem with a cupped rear end forming a steam tight connection with the valve seat in the sleeve when in operation and provided at its inner end with outlet apertures arranged at an angle to the axis of the valve stem; means adapted to swing the inner end of the valve stem radially in the slotted end of the sleeve comprising a controlling lever, a fork and a block, a shaft rigidly attached to same and connected with said fork and block; and means for rotating the valve stem.

2. In an apparatus of the class described, the combination with an inlet pipe, a rear plug, a cylindrical sleeve, a valve seat in said cylindrical sleeve, a fork and block shifting mechanism and means for operating same; of a valve stem provided with means for forming a steam tight connection with the valve seat in the sleeve and means for disengaging said valve stem from said connection and having outlet apertures at its inner end; and means for rotating said valve stem.

3. In an apparatus of the class described, the combination with an inlet pipe, a rear

plug, a cylindrical sleeve, a valve seat in said cylindrical sleeve, a valve stem rotatively mounted in said sleeve and provided with a cupped rear end and outlet apertures in its inner end, and means for rotating said valve stem; of means for shifting the valve stem radially in the slot in the inner end of the cylindrical sleeve comprising a controlling lever rigidly engaging one end of a shaft, a fork and block adapted to support the inner end of the valve stem; and means for holding same rigidly in a fixed position.

4. In an apparatus of the class described, the combination with an inlet pipe, a cylindrical sleeve, a valve seat in said cylindrical sleeve, a valve stem rotatively mounted in said sleeve and provided with a cupped rear end and outlet apertures in its inner end, means for rotating said valve stem, a fork and block adapted to shift said valve stem radially in the slot of the sleeve, means for operating same and means for holding same rigidly in a fixed position; of a rear plug adapted to extend into the cupped rear end of said valve stem, to deliver thereto straight jets of steam, and to receive the cupped end of said valve stem when same is disengaged from contact with the valve seat in the sleeve.

In witness whereof, I have hereunto set my hand this 5th day of December, 1903.

WILLIAM JOSEPH BRADLEY.
